UNITED STATES PATENT OFFICE.

CARL ROGIVUE, OF TEGL, GERMANY, ASSIGNOR TO GENERAL ELECTRIC COMPANY,
A CORPORATION OF NEW YORK.

CONDENSER PLANT FOR LOCOMOTIVES.

Application filed December 19, 1924, Serial No. 757,055, and in Germany February 6, 1924.

The present invention relates to air-cooled condensation plants for locomotives and similar self-propelled vehicles which move at comparatively high rates of speed and which are driven by elastic fluid prime movers.

The object of the invention is to provide a movable condensation plant which effectively utilizes the cooling action of the windage set up by it when in motion for directly condensing exhaust elastic fluid from a locomotive prime mover.

Heretofore, air-cooling in locomotives and the like has been in connection with water-cooled condensation plants to effect a recooling of the cooling water used in such plants. The disadvantages attending such arrangements lie in the necessity for carrying a considerable quantity of cooling water and in the complicated air-cooled recooling plant required.

By providing direct air-cooling for condensation purposes in accordance with the invention, the need for carrying large quantities of cooling water and the use of complicated air-cooled recooling means is eliminated. In providing direct air-cooling, which is effective and reliable, large cooling surfaces and means for affecting the delivery of large quantities of air thereover must be provided. This necessitates careful consideration of the relation of such air-cooling means to other and adjacent machine parts which would interfere with the air flow, the desired arrangement being such that the air flows over the cooling surfaces in substantially a straight line without obstruction.

By "direct air-cooling", as used herein, is meant cooling or condensing exhaust elastic fluid from a prime mover by air currents passed over cooling surfaces with which the exhaust elastic fluid to be condensed is in contact, that is condensing the exhaust elastic fluid directly by cooling air-currents instead of by cooling water which is later recooled by air currents.

To provide effective, direct air-cooling, the condensation plant is, in accordance with the invention, carried on a separate vehicle whereby the full width of the vehicle may be used to provide a maximum cooling surface with a given and limited height and

whereby no appreciable obstruction to air flow or space limitation is introduced by the presence of adjacent machine parts. Furthermore, the use of a separate vehicle for carrying the condensation plant permits its use with existing types of locomotives and the like wherein no space is provided for efficient condensation means.

One embodiment of the invention, particularly adapted for use in connection with railway locomotives driven by elastic-fluid prime-movers, is herein described and illustrated, and for a further consideration of what is believed to be novel and the invention, attention is now directed to the accompanying drawing, description thereof and the appended claims.

In the drawing, a railway vehicle provided with a condensation plant in accordance with the invention is diagrammatically illustrated, Fig. 1 being a side view thereof, partly in section, and Fig. 2 being a rear, end view of the same.

Referring to the drawing, 5 is any railway vehicle, such as a flat car, which is adapted to carry the apparatus of the present invention as a separate unit in a train. Mounted on the floor of the car, which is indicated at 6, in spaced relation to each other longitudinally of the car, are three surface condenser units 7, 8 and 9, each of which covers the full width of the car.

Each condenser unit comprises a condensate chamber 10 having a condensate level therein indicated at 10^a in which chamber are located a plurality of parallel air passages or cooling air tubes 11. These tubes extend between the front and rear walls of the unit and are supported thereby at their ends. The tubes thus extend longitudinally of the car and open exteriorly of the walls by which they are supported, whereby windage air currents set up by the car when in motion pass through them to effect cooling of the condensate in the chamber. The tubes in each unit are sufficient in number and properly spaced to cover substantially the entire cross section of the condensate chamber. By providing condenser units which are the full width of the car and covering substantially the entire cross section of each unit with air cooling tubes, a cooling surface of maximum area is pro-

vided in contact with the condensate for a given over-all height of car and condensate plant, the height of each condenser unit being limited to that which will permit the 5 assembled condensate plant to pass through tunnels, under bridges and the like.

Each condenser chamber is connected adjacent its top with a common exhaust elastic fluid header 12 which extends longitudinally 10 of and centrally over the car. The inlet end of the header 12 is indicated at 13, being extended in a direction to connect with the exhaust outlet of the driving elastic fluid prime mover carried by the locomotive. As the locomotive and prime mover thereon do not concern the invention, the same are not illustrated. In the present example, they may be considered to be ahead 15 of the condensation plant in the direction of travel, which last is indicated by the arrow. The exhaust header 12 therefore extends in this direction, although it will be seen that should it be desirable to position the condensation plant ahead of the locomotive, the 20 exhaust header may be easily extended to the rear for connection therewith.

The condenser chambers 10 are connected to a common receiving tank or hot well 14 located below the floor 6, the middle chamber 30 being connected directly therewith and the end chambers being connected by conduits 15. The arrangement is such that condensate from the chambers 10 flows by gravity into the hot well. The condensate 35 may then be taken from the hot well and utilized in any suitable manner, for example, it may be returned to the elastic fluid system of the locomotive with which the condensation plant is used.

40 Covering the rear wall of the condenser units 7, 8 and 9, and the inner or rear ends of the air cooling tubes 11 therein, are duplicate fan casings 16, 17 and 18, respectively, in which are located revolving centrifugal fans 19. The fans are mounted on a common shaft 20 which is driven through a suitable reduction gearing 21 by a small elastic fluid turbine 22. Bearings for the shaft are indicated at 23.

45 The turbine, shaft and gearing represent any suitable means for driving the fans 19. The turbine and gearing are preferably located as shown adjacent the front end of the car, for the reason that elastic fluid may 50 then be more easily and advantageously supplied to the turbine from the locomotive with which the condensation plant is used. However, in the case hereinbefore mentioned, that the condensation plant is to be 55 connected ahead of the locomotive with which it is used, the turbine and gearing may then be located at the rear of the car and connected with a rear extension of shaft 20.

60 The exhaust outlet of turbine 22 is indi-

cated at 24 and is directly connected with the exhaust elastic-fluid header 12 by a conduit 25. This permits the exhaust elastic fluid therefrom to be included in the main exhaust elastic fluid stream and to be delivered, as condensate, to the hot well 14. 70

Extending between condenser units 7 and 8 and between condenser units 8 and 9, in continuation of the side walls of said units, are walls 26 which thereby enclose the fan 75 casings 16 and 17. The walls 26 between condenser units 7 and 8 are not shown in order to show the interior thereat more clearly. The major portion of the fan casings do not occupy the full width or height 80 of the car, as represented by the space between lines 27 and 28, Fig. 2, and fan casings 16 and 17 are spaced from condenser units 8 and 9 respectively, so that within the walls 26 and between the adjacent condenser 85 units are provided air passages or chambers 29 about the fan casings 16 and 17 which chambers connect with the adjacent inlet ends of the air cooling tubes in condenser units 8 and 9. 90

Walls 26 are louvered, as indicated at 30, to entrain air from a frontal direction and to direct said entrained air into chambers 29 from which chambers it is received by 95 the air cooling tubes and directed thereby through the condenser units 8 and 9, each of said condenser units being thereby supplied with cooling air separately from the other.

Condenser units 7, being at the front of 100 the car with the open ends of the air cooling tubes therein directly exposed to the windage flow, requires no louvers or air passages for entraining air and directing the same through said condenser unit other than the 105 tubes alone. Although turbine 22 and gearing 21 are positioned in front of condenser unit 7, the turbine and gearing are of small size and offer little resistance to the windage flow to the air cooling tubes of said unit. 110 It is obvious that a considerable quantity of cooling air would flow through condenser units 8 and 9 without resorting to means such as the walls 26 and the louvered openings therein for entraining the windage air 115 for said condenser units.

The entrained air for each condenser unit, after passing through the cooling tubes thereof, enters the adjacent fan casing to the rear, passes through the fan, and leaves 120 the fan casing in the direction of the arrows below each fan, suitable outlet openings (not shown) being provided in the floor 6 which forms the bottom of the fan casings.

125 It will be seen that the condensation plant comprises what is substantially an air cooled surface condenser comprising separate units connected in parallel between the exhaust header and the hot well and adapted to receive cooling air in each section separately, 130

the cooling air being the windage set up by the speed of travel, which is entrained and directed through the condenser units. While three condenser units are shown in the condenser of the present example, it is obvious that a greater or lesser number of units may be used to provide a certain desired cooling capacity.

The cooling air tends to flow through the 10 air-cooling tubes at substantially the speed of the car when in motion, the rate of flow of air increasing and decreasing with the speed. To provide a higher effective speed in the windage or air flow through the cooling tubes at all higher speeds, and to maintain 15 a considerable flow of air through said tubes at relatively low speeds, a separate centrifugal fan is provided in connection with each condenser unit. The fans are preferably 20 driven by a common shaft and in a direction to create a suction upon the inner ends of the air-cooling tubes of the condenser units. For various speeds and conditions of operation, the speed of the driving 25 turbine for the fans may be regulated to provide the desired cooling effect within certain limits.

30 In each condenser unit, the cooling air intake is above the floor, while the outlet is below the floor. This arrangement prevents the warm air discharged from one unit ahead from being mixed with the air intake for the units in the rear.

35 While the invention has been herein de-
scribed in connection with a condensation
plant for elastic-fluid-prime-mover-driven
locomotives, it is not limited thereto and is
capable of other embodiments for use in
connection with any self-propelled vehicle
40 requiring a simple, effective and economical
condensation plant.

What I claim as new and desire to secure by Letters Patent of the United States is:

45 1. The combination with a vehicle, of
means carried thereby for condensing ex-
haust elastic fluid directly by air currents,
said means comprising a surface condenser
having a plurality of independent units
spaced apart longitudinally of the vehicle,
50 each of said units occupying substantially
the full width and height of the vehicle
whereby units of maximum permissible
cross-section are provided, means for utilizing
the windage air currents set up by the
55 speed of travel of the vehicle in effecting
cooling of the condenser units uniformly
over the full cross-section thereof, and means
connected with each condenser unit for ac-
celerating the flow of the air currents so util-
60 ized and exhausting the same below the ve-
hicle.

2. The combination with a vehicle, of
means carried thereby for condensing ex-
haust elastic fluid directly by air currents,
65 said means comprising a surface condenser

having a plurality of independent units spaced apart longitudinally of the vehicle and each occupying substantially the full width of said vehicle, means for directing air currents incident to the travel of the vehicle separately through each condenser unit and for discharging said air currents below the vehicle, and means connected with each condenser unit for accelerating the flow of said air currents therethrough at all speeds at which the vehicle travels and for maintaining a certain desired air flow therethrough at relatively low speeds. 70 75

3. The combination with a vehicle, of means carried thereby for condensing exhaust electric fluid directly by air currents, said means comprising a surface condenser having a plurality of independent units spaced apart longitudinally of the vehicle and each occupying substantially the full width of the vehicle, means for directing windage air currents incident to the travel of the vehicle separately through each condenser unit and for discharging said air currents below the vehicle, and means comprising a fan casing connected with each condenser unit and a suction fan in each casing for accelerating the flow of windage air currents through said condenser units. 85 90 95

4. The combination with a vehicle, of 95
means carried thereby for condensing ex-
haust elastic fluid directly by air currents,
said means comprising a surface condenser
having a plurality of independent units
spaced apart longitudinally of the vehicle 100
and each occupying substantially the full
width of the vehicle, a plurality of air pas-
sages in each unit which extend there-
through in a longitudinal direction with re-
spect to the vehicle, said direction being that 105
of the travel of the vehicle when in motion,
a separate suction fan for each condenser
unit connected with the air passages thereof
and being provided with an outlet opening
which discharges below the vehicle, certain 110
of said fans being interposed between adja-
cent condenser units, and means providing
an inlet air chamber for a condenser unit
about each of said interposed fans.

5. The combination with a vehicle, of a surface condenser mounted thereon, said condenser comprising a plurality of independent units spaced apart longitudinally of the vehicle and each occupying substantially the full width of the vehicle, a plurality of air passages in each unit which extend therethrough in a longitudinal direction with respect to the vehicle, said direction being that of the travel of the vehicle when in motion, walls between adjacent condenser units which form air chambers connected with the air passages of certain of the condenser units, louvers in said walls providing substantially frontal openings for entraining windage air currents set up by the vehicle 130 120 125 135 140

when in motion, and a separate suction fan for each condenser unit connected with the air passages thereof.

6. The combination with a vehicle, of a surface condenser mounted thereon, said condenser comprising a plurality of independent units spaced apart longitudinally of the vehicle and each occupying substantially the full width of the vehicle, a plurality of air passages in each unit which extend therethrough in a longitudinal direction with respect to the vehicle, said direction being that of the travel of the vehicle when in motion, walls between adjacent condenser units which form air chambers connected with the air passages of certain of the condenser units, louvers in said walls providing substantially frontal openings for entraining windage air currents set up by the vehicle when in motion, an exhaust elastic fluid header and a hot well between which the condenser units are connected, said header being located above the condenser units and said hot well being located below the condenser units, a separate suction fan for each condenser unit connected with the air passages thereof, and means carried by the vehicle for driving the suction fans.

7. The combination with a vehicle, of a surface condenser mounted thereon, said condenser comprising a plurality of independent units spaced apart longitudinally of the vehicle and each occupying substantially the full width of the vehicle, a plurality of air passages in each unit which extend therethrough in a longitudinal direction with respect to the vehicle, said direction being that of the travel of the vehicle when in motion, walls between adjacent condenser units which form air chambers connected with the air passages of certain of the condenser units, louvers in said walls providing substantially frontal openings for entraining windage air currents set up by the vehicle when in motion, an exhaust elastic fluid header and a hot well between which the condenser units are connected, said header being located above the condenser units and said hot well being located below the condenser units, a separate suction fan for each condenser unit connected with the air passages thereof, and means for driving the suction fans, said means comprising a common shaft on which the fans are mounted and

an elastic-fluid prime-mover mounted on the vehicle and operatively connected with the shaft.

8. The combination with a vehicle having a floor, of a surface condenser mounted thereon above said floor, said condenser comprising a plurality of separate condensate chambers spaced one behind the other along the vehicle from front to rear, air passages in each condensate chamber extending through the same from front to rear whereby windage air currents flow through said passages when the vehicle is in motion, a fan casing at the rear of each condensate chamber covering the rear ends of the air passages therein and lying in spaced relation to the adjacent condensate chamber to the rear, a fan in each casing which operates to create a suction on the rear ends of the air passages covered by each casing whereby the windage air flow through said air passages is accelerated, means providing a discharge outlet for each fan casing below the vehicle floor, and means carried by the vehicle for driving the fans.

9. The combination with a vehicle having a floor, of a surface condenser mounted thereon above said floor, said condenser comprising a plurality of separate condensate chambers spaced one behind the other along the vehicle from front to rear, air passages in each condensate chamber extending through the same from front to rear whereby windage air currents flow through said passages when the vehicle is in motion, a fan casing at the rear of each condensate chamber covering the rear ends of the air passages therein and lying in spaced relation to the adjacent condensate chamber to the rear, a fan in each casing which operates to create a suction on the rear ends of the air passages covered by each casing, whereby the windage air flow through said air passages is accelerated, means providing a discharge outlet for each fan casing below the vehicle floor, and means for driving the fans comprising a common shaft extending along the vehicle from front to rear on which shaft the fans are mounted and an elastic-fluid prime-mover mounted on the vehicle and operatively connected with the shaft.

In witness whereof, I have hereunto set my hand this 26th day of November, 1924.
CARL ROGIVUE.

Certificate of Correction.

Patent No. 1,632,624.

Granted June 14, 1927, to

CARL ROGIVUE.

It is hereby certified that error appears in the printed specification of the above-numbered patent requiring correction as follows: Page 3, line 81, claim 3, for the word "electric" read *elastic*; and that the said Letters Patent should be read with this correction therein that the same may conform to the record of the case in the Patent Office.

Signed and sealed this 19th day of July, A. D. 1927.
